UNITED STATES PATENT OFFICE.

JACOB M. MARKS, OF NEW YORK, N. Y.

DESIGN FOR A LOUD SPEAKER.

Application filed April 5, 1928. Serial No. 26,138. Term of patent 3½ years.

To all whom it may concern:

Be it known that I, JACOB M. MARKS, a citizen of the United States, residing at New York, in Bronx County, State of New York, have invented a new, original, and ornamental Design for Loud Speakers, of which the following is a specification, reference being made to the accompanying drawing, forming a part thereof.

Figure 1 is an elevational view of a loud speaker showing my new design.

Figure 2 is a side view of the loud speaker shown in Figure 1.

I claim:

The ornamental design for a loud speaker, as shown.

JACOB M. MARKS.
